(57) **CLAIM**

The ornamental design for a display screen with transitional graphical user interface as shown and described.

DESCRIPTION

FIG. 1 is the first image in a sequence for a display screen with transitional graphical user interface showing our new design; and,

FIG. 2 is the second image thereof.

The appearance of the transitional graphical user interface transitions between the images shown in FIGS. 1-2. The process or period in which one image transitions to another forms no part of the claimed design. The broken line at the perimeter of the figure illustrates the display screen and the remaining broken lines illustrate portions of the transitional graphical user interface. None of the broken lines form part of the claimed design.
